CLAIM

I claim the ornamental design for a kit for A/C window unit condenser filters, as shown and described.

DESCRIPTION

FIG. 1 is an exploded front, top and side perspective view of the kit for A/C window unit condenser filters in the open condition showing the elements used to cover the A/C window unit intake embodying the design of the present invention.

FIG. 2 is a top plan view of the container for the kit.

FIG. 3 is a bottom plan view of the container.

FIG. 4 is a side elevational view of the container, the side opposite to the side shown in FIG. 4 being identical to the side shown in FIG. 4.

FIG. 5 is a front elevational view of the container; and, FIG. 6 is a rear end elevational view of the container.

The kit shown contains a filter, tape and a knife for applying the filter over the intake area of an A/C window unit to prevent debris, insects and the like from entering the unit and plugging the condenser of the unit.
